UNITED STATES PATENT OFFICE.

JOHN B. DES ROSIERS, OF PROVIDENCE, RHODE ISLAND.

DETONATING FUSE.

1,207,511.

Specification of Letters Patent. Patented Dec. 5, 1916.

Application filed February 26, 1916. Serial No. 80,566.

To all whom it may concern:

Be it known that I, JOHN B. DES ROSIERS, a citizen of the United States, and a resident of the city and county of Providence and 5 State of Rhode Island, have invented a new and useful Improvement in Detonating Fuses, of which the following is a specification.

The object of my invention is to provide 10 a simple and efficient device for detonating the explosive charge of bombs, projectiles, torpedoes, mines or similar devices at given depths below the surface of water or after definite periods of immersion.

15 My device is simple, easy and inexpensive to manufacture and accurate and efficient in action.

In the drawings, Figure 1 is a cross section of my device as embodied in a fuse plug 20 of the usual type; Fig. 2 is an end view of my device showing indicator; Fig. 3 is a near view of the inside of the needle valve; Fig. 4 is a section of Fig. 1 at its center.

To further describe a form of my invention which I have found advantageous, 13 is a cylindrical body of brass or other suitable material which may be forced into the well of a fuse plug of the type usually applied to projectiles. This cylinder has an 25 enlarged portion 9 at its outer end for the double purpose of adding strength and giving a surface for the indicator dial 27. Slidably mounted in this body is an inner body 10 adapted to slide inside the cylinder 13 30 but with a high degree of friction. The range of motion of this inner cylinder or body is controlled by a pin 12, secured in the cylinder 13 and projecting into a slot 11 in the inner cylinder 10. By means of a 35 right angle in this slot, the inner cylinder 10 may be turned several degrees and locked in that position. The pin 12 and the slot 11, with its right angle extension, acting as a bayonet catch, well known in the art. The 40 outer extremity of this body 10 is tapered to inclose a small chamber 7; the outside of this extension is threaded and on it revolves check nut 6 and the valve cap 2 which carries the indicator 5. The end of the cylinder 10 is brought to a finely tapered point 3, which point projects through a tapered hole 25 in the valve cap 2. The cap 2 and the tapered point 3 thus operate as a needle 45 valve and moisture entering around the point 3 is conducted into the chamber 7 through the holes 26. The interior end of

the cylinder 10 is threaded to receive the auxiliary firing device 16. The inward end of the outside cylinder 13 is contracted at right angles, as at 20 and a rearward projection 21, is threaded or otherwise adapted to receive an exterior closing cap 22, which cap has an opening in its center. Between the end of the auxiliary firing device 16 and the annular seat formed by the contraction 60 of the outside cylinder 13, a recess is formed as at 17, to receive a circular percussion cap 18.

Having now briefly described the construction of my device, its operation is as 70 follows: Into the cavity 7 at the head of the inner cylinder 10, a compound is placed which can be exploded by the action of water. There are many compounds known to the chemical art, especially potash combinations, which will do this. This cavity is then closed by a thin wad 14 preferably of shellacked paper which rests on the annular seat formed by the contraction of the chamber 7. The chamber 8 is then filled with 75 black gun-powder or other suitable explosive and another wad 15 is used to close it. The auxiliary firing device 16 is then secured home, holding the wad in place. The wad 23 is then placed over the rear end of 80 the outer cylinder 13 and the cap 22 secured in place to hold it. The percussion cap 18 is then placed on its seat, the chamber 19 is filled with gunpowder or similar explosive and the inner cylinder 10 is then inserted to its proper position where it is held by the insertion and upsetting of the pin 12 in the slot 11. The check nut and the valve cap are then put in place and the entire device now carried in the outer cylinder 13, is placed in the cavity of the fuse plug of the usual form or in any position 85 so that its inner end communicates with the main explosive charge 24.

My device is now perfectly safe for storage and transportation. When it is desirable to use the same, the interior cylinder 10 is turned so that the pin 12 can slide freely in the longitudinal slot 11. The valve cap 2 is then turned to its proper setting 100 and locked by the check nut 6. When the projectile or mine, bearing this fuse is submerged, water in minute quantities passes in between the seat 25 and the point 3 of the needle valve and reaches the explosive charge in the chamber 7; the explosion is thereupon communicated to the charges in 105 110

- the chamber 8 and chamber 19 and the main explosive charge 24 (in general practice gun cotton) is detonated. In cases where the hydraulic timing device fails to operate or 5 in which it is desired to fire by similar percussion the impact of the cap 2 against any body causes the inner cylinder 10 to be driven back; the auxiliary firing device 16 then acts as a hammer, crushing the circular 10 percussion cap 18 between it and the anvil 20, formed in the body of the outer cylinder 12. The explosion of this percussion cap is communicated to the explosive in chamber 19, thence detonating the main explosive charge 24 in the usual manner. 15
- Variations in the form of this device may be made necessary to adapt it to mines, submarine mines, bombs, projectiles and other forms of explosive implement.
- Having thus briefly described the operation of an improved form of my device, I claim--
1. In a detonating fuse, a body, an inner body slidably mounted therein, a chamber in said inner body, means for admitting minute quantities of liquid to said chamber and means for controlling flow of such liquid.
  2. In a detonating fuse, a body, an inner body slidably mounted therein, a chamber in said inner body, a valve on the end of said chamber and means for regulating the admission of water to said chamber by said valve.
  3. In a detonating fuse, a body, an inner body slidably mounted therein, a chamber in said inner body, a head on said inner body, a valve in said head and means to regulate the operation of said valve.
  4. In a detonating fuse, a body, an inner body slidably mounted therein, means to control the sliding motion of said inner body, a chamber in said inner body and means to control the admission of minute quantities of liquid to said chamber.
5. In a detonating fuse, a body, an inner body slidably mounted therein, means for controlling the motion of said inner body, a chamber in said inner body, means for controlling the admission of liquid to said chamber, an interior seat on said outer body adapted to receive the thrust of said inner body and a chamber connected to said interior seat. 50
6. In a detonating fuse, a body, an inner body slidably mounted therein, a chamber in said body, means for controlling the admission of liquid to said chamber, means for controlling the motion of said interior body, an enlargement of said interior body, a circular interior seat on said outer body adapted to receive the thrust of said sliding body, a chamber connecting with said interior seat, and means for closing the end of said chamber. 55
7. In a detonating fuse, a body, an inner body slidably mounted therein, a chamber in said inner body adapted to hold explosives, means for dividing explosives in said chamber, means for admitting liquid to said chamber, means for controlling the admission of said liquid, means for locking said controlling device, means for controlling the motion of said interior body, a striking member on the rearward end of said interior body, a circular interior seat on said outer body adapted to receive the blow of said striking member, a recess between said striking member and said interior, circular seat, a chamber connecting with said interior, circular seat adapted for holding explosives and means for closing the end of said chamber. 60 70 75

In witness whereof, I have set my hand in the presence of two witnesses.

JOHN B. DES ROSIERS.
